AUXILIARY FEEDING ATTACHMENT

Wilbur Johndrew, Buffalo, N. Y.

Application February 29, 1944, Serial No. 524,423

9 Claims. (Cl. 78—48)

1

My invention relates in general to auxiliary feeding devices as applied to riveting machines and in particular to a device for automatically feeding the bucking tool or riveting anvil as it is being moved to its operative position in underneath an angularly arranged or overhanging flange of a workpiece, as for instance, the cap-strip of an airplane spar.

The principle object of my invention has been to provide an attachment for use upon the bucking tool or anvil of a riveting machine whereby the tool or anvil may be moved laterally as it is being fed vertically for engaging rivets located under an overhanging or angularly arranged cap-strip.

Another object has been to provide an auxiliary feeding attachment having a templet device carried by the relatively movable ram and cylinder of the riveting machine.

A further object has been to provide a compensating device carried by the cylinder of the machine for controlling the lateral feeding means thereof and for association with a templet device so that relative axial movement of the ram with relation to the cylinder will cause lateral movement of the ram and cylinder with respect to the workpiece.

Another object has been to provide a templet device having interchangeable guide bars whereby a separate guide bar may be initially prepared for each workpiece to be riveted, and quickly and easily inserted at any desired time.

The above objects and advantages have been accomplished by the accompanying drawings of which:

Fig. 1 shows a fragmentary side elevation of a riveting machine with my device in position thereon.

Fig. 2 is a fragmentary sectional elevation thereof taken on line II—II of Fig. 1.

Fig. 3 is a fragmentary sectional elevation taken on line III—III of Fig. 1.

Fig. 4 is an enlarged front elevation of my device.

Fig. 5 is a plan view thereof.

Fig. 6 is an end elevation thereof.

Fig. 7 is an enlarged plan view of the templet device of my attachment.

Fig. 8 is a sectional elevation of the templet device taken on line VIII—VIII of Fig. 7.

Fig. 9 is an enlarged view of the lateral feeding mechanism for the bucking tool and riveting anvil of the riveting machine with which my invention is used.

Fig. 10 is a diagrammatic view showing the electric circuits of my device.

As shown in Figs. 1, 2 and 3 my invention is applicable to a riveting machine having a riveting unit 15 and a bucking unit 16. The riveting unit is mounted upon the transverse ways 20 extending longitudinally of the machine. The bucking unit is movable over longitudinal ways 21, extending longitudinally of the machine. This unit is held vertically when not in use or when being adjusted by means of supporting angles 22 carried by the ways 21 and engaged by rollers 23 carried by the head 24 of the unit. The units are moved, preferably in unison, by means of a feed motor 25. This motor is connected to the feed gears 26 and 30 by means of drive shafts 31, one extending upwardly and the other extending downwardly from the motor. The feed gear 30 is non-rotatably mounted upon a drive sleeve 32, which is interiorly screw-threaded to engage the unit feed screw 33. There are, of course, two feed screws provided, one for the bucking unit and the other for the riveting unit. The drive sleeve of each of the feed screws is rotatably mounted against axial movement within suitable anti-friction bearings 34. The sleeves and shafts are passed through suitable openings formed in the end plate 35 of the housing of the riveting machine.

My auxiliary attachment comprises a compensating device 37 carried by the ram cylinder and the worktable for controlling the lateral movements of said cylinder, and a templet device 38 carried by the ram of the machine. The attachment may be carried by either the bucking unit 16 or riveting unit 15. For convenience of illustration, my invention is illustrated as applied to the bucking unit of the machine, and will hereafter be described in connection therewith, it being obvious that the device is also applicable for use in connection with the riveting unit. The compensating device comprises a mounting plate 40 which is secured to the cylinder 41. A mounting bracket 42 is slidably supported by the mounting plate, and has its longitudinal edges mounted between rollers 43 carried by the mounting plate. The mounting bracket is provided with a longitudinal slot 44 which engages a stop pin 45 carried by the mounting plate, whereby the mounting bracket will be prevented from becoming disengaged from the rollers 43 during its longitudinal movement. A helical spring 46, having one end engaged with a pin 50 carried by the mounting plate 40, and its other end engaged by a pin 47 carried by the mounting bracket, serves to keep the bracket urged to the left as shown in Fig. 1.

55 Mounted for oscillation upon the mounting

bracket 42 is a rocker arm 51, which is mounted upon trunnion bearings 52. This arm is kept urged in clockwise direction by means of a helical spring 53, having one end bearing against an arm 54 of a bracket 55 and the other end bearing against the upper end of the rocker arm. The bracket 55, which is carried by the mounting bracket 42, is provided with an arm 56 at the opposite side of the rocker arm which carries an adjustable stop screw 60, for limiting the clockwise movement of the rocker arm. The rocker arm carries an adjustable rocker arm rod 61 which passes therethrough and which has a plurality of semi-circular recesses 62 formed therein for engagement with a detent pin 63. This pin is carried by a spring plate 64, secured at one end to one side of the rocker arm which serves to keep the pin engaged with the selected groove, but should it be desired to adjust the vertical relationship of the rocker arm and rod, the rod may be pushed axially to bring another groove in registration with the pin 63. The rocker arm carries a roller 65 at its lower end which engages with a guide angle 66 carried by the work table 67 of the riveting machine and which is kept in contact therewith by means of the spring 53. This guide angle which extends substantially parallel with the rivet pattern of the cap-strip 70 of the spar 71, thus providing a fixed member for co-operation with the roller 65 of the rocker arm, as will be hereinafter described.

The mounting bracket 42 is provided with a switch platform 72 on one side of which is mounted an electric switch 73, a similar switch 74 being secured to the other side thereof. The switches are arranged preferably equidistantly on each side of the trunnion bearings 52 of the rocker arm, and the rocker arm is provided with adjusting screws 75 and 76, for engagement with the switches 73 and 74, respectively. These screws are preferably mounted upon a screw plate 80 carried by the rocker arm.

The templet device 38 of my invention is secured to the ram 81 of the riveting machine, and comprises a stationary guide 82 having an attaching flange 83 for securement to a plate 84 carried by the ram. Slidably carried by this guide is a bar slipper 85. The slipper is held in place by means of slipper plates 86 secured to the back face of the slipper and each engaging a recess 90 formed in the back face of the stationary guide. The stationary guide is provided with a longitudinal groove 91 in which is mounted a gauge bar 92. This gauge bar is limited in its inward movement along the groove 91 by means of a stop pin 93 carried by the stationary guide, and its outer end is retained in place by means of a retaining pin 94 which passes through the stationary guide and the gauge bar. The gauge bar is formed with a plurality of recesses 95 arranged at predetermined points and in accordance with the various laterally arranged operating stations on the workpiece. By this arrangement a separate gauge bar may be provided for each workpiece and the proper bar may be quickly inserted in the guide. The bar slipper carries a bullet catch 96 having a head 97 for engagement with either of the recesses 95. This catch is mounted within a sleeve 100 carried by the slipper and has an index knob 101 secured to its outer end whereby it may be moved axially. A spring 102 is mounted within a recess 103 formed in the sleeve 100 which serves to press the catch outwardly for engagement with a registering recess. When a

workpiece having differently located lateral stations is to be operated upon, the gauge bar 92 may be removed by withdrawing the retaining pin 94, and replaced by a bar having apertures arranged in accordance with the workpiece.

As shown in Fig. 4, the upper flange 104 of the cap-strip 70 overhangs the inner rivet 105, so that the bucking tool 108 cannot be moved downwardly in a vertical plane but must be moved inwardly 10 as it approaches the rivets. The final inward position of the tool when engaged with the heads of the rivets is shown in dot and dash lines. The bucking tool 108, as shown, is relieved on the side facing the flange 104 of the cap-strip 70 whereby 15 it will clear this flange when the tool engages the rivets 105. In order to accomplish the lateral movement of the bucking tool as the ram 81 is moved downwardly I employ a templet bar 106 which is carried by the slipper 85. This bar is mounted in a recess 107 formed in the slipper 20 and extends upwardly therefrom. It is adjustable and clamped in position by means of a clamp screw 110. The right hand edge of the templet bar is provided with operating surfaces 25 113 and 114 which engage with a templet roller 111 carried by the mounting bracket. These surfaces are held firmly against the roller by means of the spring 46, and a spring clip 112 is carried by the templet roller stud in resilient 30 engagement with the left hand edge of the templet bar, whereby it is kept in proper alignment. The operating surface 113 of the templet bar is located in the plane spaced from the plane in which the surface 114 is located and joined thereto preferably by an inclined surface 115 so that as 35 the templet bar is moved downwardly in relation to the roller 111, the roller will ride across the inclined surface 115 from the surface 114 to the surface 113. During such movement the mounting bracket 42 will be moved to the left in the mounting plate 40 under the tension of the spring 46 and as it is so moved the rocker arm 61 will be oscillated slightly in counter-clockwise direction upon its trunnions 52 due to the engagement of 40 the roller 65 with the guide angle 66, thereby causing the switch 73 to be closed. This switch is so connected in the control circuit as to cause the cylinder and ram to be moved to the right until the bucking tool has been moved to the 45 position where it will occupy the dot and dash line position shown in Fig. 4, at which time the rocker arm with its rod will be in neutral position. Such movement may be continuous or increment by increment each movement serving to 50 bring the rocker arm again to its neutral position whereby the lateral movement of the cylinder and ram will be stopped. If, when the rocker arm has reached its neutral position, the templet roller has not yet reached the surface 113, further 55 downward movement of the ram will cause further movement of the mounting bracket and consequent repeated operation of the switch 73. Consequently, as the bucking tool is being moved downwardly it is also being moved inwardly until 60 it comes to its final position shown in the dot and dash lines.

Obviously, when the bucking tool is elevated to disengage the workpiece, the templet bar will travel along the roller 111 and cause it to move 65 up the incline 115 from the surface 113 to the surface 114; and, as it does so, the mounting bracket will be moved relatively to the mounting plate and thereby cause clockwise rotation of the rocker arm on its trunnions. This will operate the 70 switch 74 to cause the mounting bracket 42 and

its associated parts to be moved to the left as viewed in Fig. 4, thereby moving the anvil 103 laterally so that, as it is elevated, it will clear the flange 104.

Referring now to Fig. 10 where I show my device connected in a suitable electric circuit, the feed motor 25, which is of the reversing type, is diagrammatically represented. Since the bucking unit must be operated in opposite directions, two contactors 120 and 121 are provided for actuating the motor. The contactor 120 is provided with an operating coil 122, and the contactor 121 is provided with an operating coil 123. Three normally open contacts 124, 125 and 126 are provided on the contactor 120, and three normally open contacts 130, 131 and 132 are provided on the contactor 121. The power lines are represented at 133, 134 and 135. The contacts 124 and 130 are connected to the power line 133; the contacts 125 and 131 are connected to the power line 134; and contacts 126 and 132 are connected to the power line 135. The contacts 124, 125 and 126 are connected by suitable leads to the motor 25 for operation thereof in one direction, and the contacts 130, 131 and 132 are connected to the motor for operation thereof in reverse direction. The operating coils 122 and 123 of the contactors 120 and 121, respectively each receive current from the power line 135. The switches 73 and 74 are represented in the diagram and each has one of its terminals connected to a common point 143 which, in turn, is connected to the power line 133. The other terminals 144 and 145 of these switches are connected respectively to the opposite side of the operating coils 122 and 123. When the rocker arm 51 is oscillated in counter-clockwise direction, the switch 73 will be closed as hereinbefore described, and when the rocker arm is moved in clockwise direction, the switch 74 will be closed, thus actuating the contactor to which this actuating switch is connected. Obviously when either contactor is actuated, the circuits thereof are closed by its contacts, and the motor 25 is operated to rotate the feed screws 33 in the correct direction to cause the desired lateral movement of the cylinder and ram.

Having thus described my invention, what I claim is:

1. In a riveting machine, the combination with the cylinder, the reciprocating ram, the lateral feeding means and the worktable thereof, of an auxiliary feeding attachment comprising a compensating device carried by said cylinder for controlling said feeding means, said device having a stationary mounting plate, a laterally reciprocating bracket carried by said plate, an oscillating arm carried by said plate, a laterally fixed guide member carried by said worktable, said arm having its lower end in engagement with said laterally fixed member, switch means carried by said bracket and actuated by movement of said oscillating arm, said switch means being associated with said feeding means to cause said cylinder and said ram to be moved laterally of said worktable, and means carried by said ram and actuated during the working stroke thereof for causing said feeding means to be operated.

2. In a riveting machine, the combination with the cylinder, the reciprocating ram, the lateral feeding means, and the worktable thereof, of an auxiliary feeding attachment comprising a compensating device carried by said cylinder for controlling said feeding means, said compensating device having a fixed member and a mov-

able member, a stationary guide member carried by said worktable, an oscillating arm carried by said movable member and having its lower end in engagement with said stationary member, and a templet device co-operating with said compensating device, and having a templet bar coacting with the movable member of said compensating device to cause lateral movement thereof.

3. In a riveting machine, the combination with the cylinder, the reciprocating ram, the lateral feeding means, and the worktable thereof, of an auxiliary feeding attachment comprising a compensating device carried by said cylinder for controlling said feeding means, said compensating device having a fixed member and a movable member, a stationary guide member carried by said worktable, an oscillating arm carried by said movable member and having its lower end in engagement with said stationary member, and a templet device co-operating with said compensating device, said templet device comprising a stationary guide carried by said ram, a slipper adjustably mounted upon said guide, and a templet bar adjustably carried by said slipper and associated with the movable member of said compensating device to cause lateral movement thereof.

4. In a riveting machine, the combination with the cylinder, the reciprocating ram, the lateral feeding means, and the worktable thereof, of an auxiliary feeding attachment comprising a compensating device carried by said cylinder for controlling said feeding means, said compensating device having a fixed member and a movable member, a stationary guide member carried by said worktable, an oscillating arm carried by said movable member and having its lower end in engagement with said stationary member and a templet device co-operating with said compensating device, said templet device comprising a stationary guide carried by said ram, a gauge bar detachably carried by said guide and formed with a plurality of predetermined apertures, a slipper mounted upon said guide, detent means carried by said slipper for engagement with one of the apertures of said gauge bar, and a templet bar adjustably carried by said slipper and co-operating with the movable member of said compensating device to cause lateral movement thereof.

5. In a riveting machine, the combination with the cylinder, the reciprocating ram, the lateral feeding means and the worktable thereof, of an auxiliary feeding attachment comprising a compensating device carried by said cylinder for controlling said feeding means, said compensating device having a fixed member and a movable member, a stationary guide member carried by said worktable, an oscillating arm carried by said movable member and having its lower end in engagement with said stationary member and a templet bar carried by said ram and coacting with said compensating device, said templet bar having two spaced working surfaces lying in spaced planes, said working surfaces having co-operative connection with the movable member of said compensating device to cause lateral relative movement of said cylinder and ram as said ram moves on its working stroke.

6. In a riveting machine, the combination with the cylinder, the reciprocating ram, the lateral feeding means, and the worktable thereof, of an auxiliary feeding attachment comprising a compensating device carried by said cylinder for controlling said feeding means, said compen-

75 for controlling said feeding means, said compen-

sating device having a fixed member and a movable member, a stationary guide member carried by said worktable, an oscillating arm carried by said movable member and having its lower end in engagement with said stationary member and a templet bar carried by said ram and coacting with said compensating device, said templet bar having two spaced working surfaces lying in spaced parallel planes and being connected by an inclined surface, said working surfaces having co-operative connection with the movable member of said compensating device to cause lateral relative movement of said cylinder and ram as said ram moves on its working stroke.

7. A feeding attachment for riveting machines, comprising a compensating device, comprising a stationary member, a reciprocating member carried by said stationary member, an oscillating arm carried by said reciprocating member and having a downwardly extending arm, spring means for urging said arm in one direction, switch means mounted upon said movable member and actuated by the oscillating movement of said arm, said attachment having a templet device movable relatively with said compensating device, said templet device comprising a stationary guide, a slipper adjustably carried by said guide, and a templet bar carried by said slipper and coacting with the movable member of said compensating device for causing lateral movement of said attachment in relation to a workpiece when said devices are moved relatively.

8. A feeding attachment for riveting machines, comprising a compensating device, comprising a stationary member, a reciprocating member carried by said stationary member, an oscillating arm carried by said reciprocating member and having a downwardly extending arm, spring means for urging said arm in one direction, switch means mounted upon said movable member and actuated by the oscillating movement of said arm, said attachment having a templet device movable relatively with said compensating device, said templet device comprising a stationary guide, a detachable gauge bar carried by said guide and formed with a plurality of apertures, a slipper mounted upon said guide, detent means carried by said slipper for engagement with one of the apertures of said gauge bar, and a templet bar adjustably carried by said slipper and co-

operating with the movable member of said compensating device to cause lateral movement of said attachment in relation to a workpiece when said devices move relatively.

9. In a riveting machine, the combination with the cylinder, the reciprocating ram, and the lateral feeding means thereof, of an auxiliary feeding attachment comprising a compensating device mounted upon said cylinder for controlling said feeding means and having a part engageable with a workpiece, said device having a stationary mounting plate, a laterally reciprocating bracket carried by said plate, means carried by said ram and co-operating with said compensating device for causing said bracket to be moved relatively to said cylinder in lateral direction, and electric switch means carried by said bracket and actuated by the reciprocating movement of said bracket to cause said cylinder and said ram to be moved laterally by said feeding means.
